UNITED STATES PATENT OFFICE.

CHARLES H. VIOL, OF PITTSBURGH, PENNSYLVANIA, ASSIGNOR TO STANDARD CHEMICAL COMPANY, OF PITTSBURGH, PENNSYLVANIA.

RADIUM APPLICATOR.

Application filed September 29, 1920. Serial No. 413,519.

To all whom it may concern:

Be it known that I, CHARLES H. VIOL, a citizen of the United States, and a resident of Pittsburgh, in the county of Allegheny and State of Pennsylvania, have invented 5 certain new and useful Improvements in Radium Applicators; and I do hereby declare the following to be a full, clear, and exact description of the invention, such as 10 will enable others skilled in the art to which it appertains to make and use the same.

This invention relates to an improvement in applicators of the needle type and more particularly to such in which the application 15 of radioactive rays to various forms of tumor growths is contemplated.

One object of the invention is to so construct a needle applicator for the administration of radium or other radioactive substances to tumor or other growths, that it 20 shall be sufficiently strong to permit penetration into a tumor without liability of breaking or bending; so that it shall effectually resist corrosion due to the effect of body fluids, and so that the radium or other 25 radioactive substance shall be efficiently and permanently sealed within the device to guard against possibility of loss.

With this and other objects in view, the 30 invention consists in certain novel features of construction and combinations of parts as hereinafter set forth and pointed out in the claims.

In the accompanying drawings, Figure 1 35 is a longitudinal sectional view of an applicator embodying my improvement, and Figure 2 is a transverse sectional view.

1 represents the body of the applicator which will preferably be made of steel or 40 some hard strong non-corrosive metal or alloy and may be gold plated to guard against corrosion, and I have found that with the use of stainless steel and Monel metal, the gold plating may be dispensed with. The body 1 of the applicator is provided at its solid end with an eye 2, said solid part of the shaft serving to give a 45 strong holding grip for the forceps used in inserting the needle while the eye serves to hold a thread or wire used to withdraw the needle. The body 1 is formed with a chamber 50 55 to contain radium salt or other radioactive compound. One end of this chamber is closed as at 4 and its other end is normally open to permit the insertion of the radium

salt or other radioactive compound, and after said chamber shall have been charged, its forward end will be closed by the butt portion 5 of a needle point 6. The butt 5 of the needle enters the end of the chamber 60 as a plug and will then be soldered or otherwise permanently fixed in place so that it shall become in effect a permanent part of the device and obviate possibility of the escape of the radioactive material or any 65 minute portion thereof.

My improved applicator is substantial in construction and is not liable to breakage or bending and the escape of the expensive radium salt or radioactive compound is effectually prevented. 70

Having fully described my invention what I claim as new and desire to secure by Letters Patent, is:—

1. A radium applicator of the needle type 75 comprising a body portion having a chamber permanently closed at its rear end and a pointed member closing the forward end of said chamber.

2. A metal applicator of the needle type, 80 comprising a rigid body having a chamber for radio-active substance permanently closed at its rear end, and means for permanently closing the forward end of said chamber after the introduction thereinto of the 85 radio-active substance.

3. A metal applicator, comprising a body made from a strong, hard and non-corrosive metal or alloy and having a chamber for radium salt or other radio-active substance, 90 and a needle point having a butt portion entering said chamber and permitting permanent closing of the same.

4. An applicator, comprising a body made from any suitable hard, strong, non-corrosive metal or alloy and having a radium chamber permanently closed at one end, a plug permanently secured in the other end of said chamber and provided with a needle point, said body having its rear end constituted of a solid shaft permitting greatest strength when the needle is being inserted, and means to receive a withdrawing device. 95 100

In testimony whereof, I have signed this specification in the presence of two subscribing witnesses. 105

CHARLES H. VIOL.
